UNITED STATES PATENT OFFICE.

CHARLES W. STERLING AND JOHN J. RETTLER, OF APPLETON, WISCONSIN.

PHONOGRAPH-CABINET.

1,371,944.

Specification of Letters Patent. Patented Mar. 15, 1921.

Application filed April 18, 1918. Serial No. 229,332.

To all whom it may concern:

Be it known that we, CHARLES W. STERLING and JOHN J. RETTLER, citizens of the United States, residing at Appleton, in the 5 county of Outagamie and State of Wisconsin, have invented certain new and useful Improvements in Phonograph-Cabinets, of which the following is a specification.

This invention relates to improvements in 10 furniture and it is the principal object of the invention to provide a novel form of phonograph cabinet which is of such construction as will permit the rotating of the phonograph receiving compartment and the 15 record receiving compartment to any desired position and independently of each other should it be desired, thus rendering the same exceedingly convenient and enabling the direction of travel of sound to be 20 varied as desired and at the same time permitting independent adjustment of the receiving compartment to afford access thereto.

The improvements in the details and arrangement of parts will be apparent from 25 an inspection of the accompanying drawings, in connection with the specific description hereinafter contained, and wherein the preferred embodiment of the invention is 30 disclosed for the purpose of imparting a full understanding of the same.

In the drawings:

Figure 1 is a vertical section through the improved cabinet,

Fig. 2 is a horizontal section taken on the line 2—2 of Fig. 1, and

Fig. 3 is a similar view taken on the line 3—3 of Fig. 1.

Having more particular reference to the 40 drawings, in connection with which like reference characters will refer to corresponding parts throughout the several views, 1 represents the base of the cabinet, the same 45 having suitable casters 2 arranged upon the under side thereof for an obvious purpose and being octagonal in shape. Supported 50 upon the upper side of the base 1 is an octagonal bearing shelf or table 3 which is adapted to be engaged by the outer marginal 55 portions of a similarly shaped cabinet 4; said cabinet having a depending pivot pin 5 secured to the bottom portion thereof centrally of the same and engaged with the central portion of the base 1. In this connection, it is of course to be understood that the 55 cabinet 4 may be and preferably is provided

with a suitable form of door 6 supported by vertically disposed hinges in order that access can be had to the interior thereof for various purposes.

Arranged upon the upper side of the top 60 of the rotatable cabinet 4 is a second octagonal supporting shelf or table 7 which is adapted to be engaged by the outer marginal portions of an octagonal phonograph receiving receptacle or compartment 8, which as will be noted carries a centrally located pivot pin 9 upon its bottom, said pin being engaged in a suitable bearing formed centrally of the top of the cabinet 4. The casing 8 is provided with a suitable form of cover or closure 10 whereby the same may be effectually closed when not in use.

It may be here noted, that shelves or the like can be arranged in the cabinet 4 such as 75 conditions or preference may dictate in order that records or like matter may be stored in indexed order therein.

From the foregoing, it will be readily understood by persons skilled in the art that 80 we have provided an exceedingly simple and efficient form of phonograph cabinet, which by reason of its peculiar construction may have either of the compartments thereof rotated either independently or collectively to any desired position. Thus, it will be understood that the casing 8 can be varied in position in order that the direction of sound may be transmitted to any desired point. Further, the cabinet 4 may be rotated to a point convenient to the operator or user in order that records may be removed or placed therein.

If desired, roller bearings may be arranged in those portions of the compartments 95 4 and 8 having engagement with the tables 3 and 7 in order that the same may be freely turned; this being clearly within the scope of the invention.

As above indicated, we do not wish to be 100 understood as confining the invention to the particular embodiment chosen for illustration herein, nor to the exact construction, arrangement and adaption of parts shown and described, but we reserve the right to 105 make any changes and alterations that fairly fall within the spirit and scope of the invention.

We claim:

A device of the character described comprising a base, an octagonal supporting table positioned upon the base, a centrally

disposed socket carried by the table, a record receiving cabinet mounted upon the table and provided with a door permitting access to the interior thereof, a short pivot pin carried by the cabinet fitting into the socket to rotatably support the cabinet for movement on a vertical axis, a spacing sleeve for said pin between the base and bottom of the cabinet, a second octagonal table arranged upon the top of the cabinet, a socket carried by the second table, and a phonograph receiving receptacle supported upon the second table provided with a short pivot pin re-

ceived within the second mentioned socket to rotatably support the receptacle, a spacing sleeve for said last named pin between the top of the cabinet and receptacle, said cabinet and receptacle being independently movable to permit the sound outlet of the phonograph and the door of the cabinet to be moved into various angular positions. ¹⁵

In testimony whereof we affix our signatures hereto.

CHARLES W. STERLING,
JOHN J. RETTLER.
